(57) **CLAIM**

I claim the ornamental design for a chair, as shown and
described.

DESCRIPTION

FIG. 1 is a perspective view of a chair embodying the
design.

FIG. 2 is a first side view of the chair of FIG. 1.

FIG. 3 is a second side view of the chair of FIG. 1.

FIG. 4 is a front view of the chair of FIG. 1.

FIG. 5 is a rear view of the chair of FIG. 1.

FIG. 6 is a top view of the chair of FIG. 1.

FIG. 7 is a bottom view of the chair of FIG. 1.

FIG. 8 is a perspective view of another chair embodying the
design.

FIG. 9 is a first side view of the chair of FIG. 8.

FIG. 10 is a second side view of the chair of FIG. 8.

FIG. 11 is a front view of the chair of FIG. 8.

FIG. 12 is a rear view of the chair of FIG. 8.

FIG. 13 is a top view of the chair of FIG. 8.

FIG. 14 is a bottom view of the chair of FIG. 8.

FIG. 15 is a perspective view of another chair embodying
the design.

FIG. 16 is a first side of the chair of FIG. 15.

FIG. 17 is a second side view of the chair of FIG. 15.

FIG. 18 is a front view of the chair and of FIG. 15.

FIG. 19 is a rear view of the chair of FIG. 15.

FIG. 20 is a top view of the chair of FIG. 15.

FIG. 21 is a bottom view of the chair of FIG. 15.

FIG. 22 is a perspective view of another chair embodying
the design.

FIG. 23 is a first side view of the chair of FIG. 22.

FIG. 24 is a second side view of the chair and of FIG. 22.

FIG. 25 is a front view of the chair of FIG. 22.

FIG. 26 is a rear view of the chair of FIG. 22.

(Continued)

FIG. 27 is a top view of the chair of FIG. 22; and, FIG. 28 is a bottom view of the chair of FIG. 22. Portions of the chair shown in broken lines form no part of the claimed design.

1 Claim, 28 Drawing Sheets
